Primary Examiner — Shawn T Gingrich*Assistant Examiner* — Bryan Nolan Melvin(74) *Attorney, Agent, or Firm* — Scully Scott Murphy and Presser(57) **CLAIM**

The ornamental design for an electronic control unit, as shown and described.

DESCRIPTION

FIG. 1 is a front perspective view of the electronic control unit showing my new and ornamental design;

FIG. 2 is a rear perspective view thereof;

FIG. 3 is a top plan view thereof;

FIG. 4 is a bottom plan view thereof;

FIG. 5 is a side elevation view thereof;

FIG. 6 is an alternate side elevation view thereof;

FIG. 7 is a front elevation view thereof; and,

FIG. 8 is a rear elevation view thereof.

The portions of the electronic control unit shown in broken lines in the figures attached hereto form no part of the claimed design.

1 Claim, 8 Drawing Sheets(56)
